(57) **CLAIM**

The ornamental design for a display screen with transitional graphical user interface, as shown and described.

DESCRIPTION

FIG. 1 is a front view of a first image in a sequence of a display screen with a transitional graphical user interface. FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of an eighth image thereof; FIG. 9 is a front view of a ninth image thereof; and, FIG. 10 is a front view of a tenth image thereof.

The appearance of the graphical user interface transitions between the images shown in FIGS. 1-10.

The process or period in which one image transitions to another image forms no part of the claimed design.

The outermost solid-line rectangle illustrates the perimeter of a display screen. The broken lines outside this perimeter illustrate a user device. The broken lines within this perimeter illustrate features of a graphical user interface. The broken lines form no part of the claimed design.
